UNITED STATES PATENT OFFICE

BERNARD T. LEVEQUE, OF WENHAM, MASSACHUSETTS, ASSIGNOR TO UNITED SHOE MACHINERY CORPORATION, OF PATERSON, NEW JERSEY, A CORPORATION OF NEW JERSEY

SEWING MACHINE

Application filed January 15, 1930. Serial No. 420,876.

The invention relates to sewing machines and has for its object the provision of a safety device adapted for use in a machine employing a shuttle which operates in the path of movement of the needle to prevent the shuttle from coming into interference with the needle in the event of an interruption of the proper timing of these parts.

With this object in view, one feature of the invention consists in the provision in a sewing machine employing a shuttle which operates in the path of movement of the needle, of mechanism rendered operative upon interruption of the proper timing of the needle and shuttle to move these parts relatively out of operative relationship. In its preferred form, this feature of the invention contemplates the provision of mechanism which is rendered operative upon interference with the timing of the shuttle to withdraw the shuttle casing and the shuttle from operative position to prevent interference of the shuttle with the needle.

The several features of the invention consist also in the devices, combinations and arrangement of parts hereinafter described and claimed which together with the advantages to be obtained thereby will be readily understood by one skilled in the art from the following description taken in connection with the accompanying drawings of which Fig. 1 is a view in right side elevation of a portion of the head of a shoe sewing machine illustrating particularly the shuttle and its actuating mechanism; Fig. 2 is a view similar to Fig. 1 with the shuttle drawn back into inoperative position out of line with the needle; Fig. 3 is a detail sectional view in side elevation of the supporting connections for the slide on which the shuttle is mounted; and Fig. 4 is a sectional view taken on the line 4 of Fig. 2.

The invention is herein disclosed as embodied in an outsole shoe sewing machine of the McKay type employing a straight hook needle, and a shuttle which acts in timed relation with the needle, taking the loop directly from the needle hook. A machine of this type is ordinarily provided with means for disconnecting the shuttle automatically

from its driving mechanism whenever the shuttle becomes jammed for any reason, and thus to prevent possible breakage of parts. Inasmuch as the shuttle with the construction herein disclosed operates directly in the needle path, this interruption of the timing of the shuttle with relation to the needle may cause the needle on its downward stroke to be brought into interference with the shuttle hook with consequent damage to the parts. In order to obviate this danger, the shuttle housing in the present construction is slidably mounted on the machine frame, and mechanism is provided which acts automatically upon interruption of the timing of the shuttle with relation to the needle to withdraw the shuttle casing and the shuttle from operative position out of line with the descending needle.

Referring more specifically to the drawings, the needle is indicated at 2 secured to the lower end of a needle bar 4, and the shuttle at 6, provided with a hook 8, mounted in a casing 10 which is in turn secured to a bracket 12. The shuttle is of the oscillatory type and is driven in the usual manner by means of a lever arm 14 secured to the forward end of a rock shaft 16 which is continuously oscillated during the operation of the machine in timed relation to the needle. The lever arm 14 is connected at its free end through universal joints and a link 18 with an arm 20 secured to one end of a sleeve 22 which is mounted to turn on the stud 24 rigidly secured on the bracket 12. The sleeve is also provided with a downwardly extending arm 26 which carries a gear segment 28 meshing with a pinion 30 which is loosely sleeved on the driving shaft 32 of the shuttle. The pinion 30 is given a continuous oscillatory movement through these connections from the lever arm 14 during the continued operation of the machine.

The pinion 30 is normally held in driving relation to the shuttle by means of a clutch mechanism which acts automatically when excessive strain is placed on this mechanism through jamming of the shuttle to disconnect the shuttle from the pinion 30. This mechanism comprises a sleeve 34 keyed to ro-

- tate with the shuttle driving shaft 32 and provided with a clutch face 36 which is adapted to engage with a corresponding clutch surface 38 formed on the pinion 30.
- 6 The sleeve 34 is yieldingly forced in a direction to hold the clutch surface in engagement by means of a compression spring 40 which is interposed between the sleeve 34 and a nut 42 secured to the end of the shuttle driving shaft 32.
- 10 If the shuttle for any reason becomes jammed, the increased strain on the clutch surfaces 36 and 38 will cause these parts to move relatively to each other, forcing the sleeve 34 back against the pressure of the spring 40 to disconnect the driving shaft 32 from the continuously oscillating pinion 30.
- In order to permit the shuttle to be moved out of line with the descending needle upon interruption of the timing of the shuttle, as
- 20 above described, the shuttle housing or casing 10 and the bracket 12 are secured to the forward end of a slide 44 which is provided with a raised section or rib 45 adapted to fit into a corresponding groove or guideway 46 formed on a fixed portion of the machine frame. The slide 44 is held in position with the rib 45 engaging the guideway 46 to determine the direction of movement of the slide by means of a cover member or plate 47
- 25 which is rigidly clamped to two bolts 48. These bolts extend upwardly through corresponding slots 50 in the slide 44 and are screw-threaded into the machine frame. Mechanism for actuating the slide 44 to move
- 30 the shuttle out of line with the descending needle upon interruption of the timing of the shuttle comprises a compression spring 52 which is secured at one end to a pin 54 fixed on the machine frame, and at its other end to
- 35 a pin 56 secured to the slide 44. The slide 44 and the shuttle are normally held in operating position against the pressure of the spring 52 by means of a latch lever 58 which is pivotally secured at 60 to the fixed cover
- 40 plate 47 of the guideway and provided with a notched portion 62 which is adapted to engage with a corresponding abutment 64 on the slide 44. A downwardly extending arm of the latch lever 58 is provided with a roll
- 45 66 which is adapted to engage with a flange 68 on the clutch sleeve 34 keyed to the shuttle driving shaft 32. When the clutch sleeve 34 is moved against the pressure of the spring 40 to disengage the shuttle from its driving
- 50 mechanism as above described, the flange 68 will engage with the roll 66 and turn the latch lever 58 about its pivot to release the slide 44 which is then withdrawn out of operating position by the action of the compression spring 52.

The invention having been described, what is claimed is:

1. In a sewing machine, the combination with a needle, of a shuttle moving in timed relation to the needle in the needle path, and

means rendered operative upon disturbance of the timing of the shuttle to move the shuttle out of the needle path.

2. In a sewing machine, the combination with a needle, of a shuttle moving in timed relation to the needle in the needle path, a support for the shuttle, and means rendered operative upon interference with the timing of the shuttle to move the support to carry the shuttle out of the needle path.

3. In a sewing machine, the combination with a needle, of a shuttle, a support on which the shuttle is mounted to operate, mechanism for driving the shuttle in timed relation to the needle, a slip joint between the shuttle and its driving mechanism, and means rendered operative upon the slipping of said joint for actuating the support to move the shuttle away from the needle.

4. In a sewing machine, the combination with a needle, of a shuttle, a support for the shuttle, a shaft rotatably mounted in the support to drive the shuttle, mechanism for driving the shuttle in timed relation to the needle, a slip joint between the shuttle and the driving mechanism comprising a sleeve keyed to slide on the shaft, spring means tending to move the shuttle out of operative position, a latch tending normally to hold the support and shuttle in operative position, and connections rendered operative by the movement of the said sleeve to break the slip joint, to disengage the said latch.

5. In a sewing machine, the combination with a needle, of a shuttle, a support for the shuttle, a shuttle driver comprising a shaft mounted to drive the shuttle, mechanism for actuating the driver to drive the shuttle in timed relation to the needle, a slip joint between the shuttle and the said actuating mechanism comprising a sleeve keyed to slide on the shaft, and a cooperating gear member mounted concentrically with the sleeve and driven by said actuating mechanism, spring means tending to hold the sleeve in engagement with the gear member to prevent slipping, a flange formed on the sleeve, spring means tending to move the support and shuttle out of operative position, and a retaining latch arranged to be actuated by contact with the flange upon slipping of the joint and consequent axial movement of the sleeve to permit movement of the support and shuttle out of the path of the needle.

6. In a sewing machine, the combination with a needle, of a shuttle, a support for the shuttle comprising a slide adapted to move the shuttle into and out of operative position, a guideway for the said slide comprising a track, a cover plate to hold the slide in contact with the track, and bolts to which the cover plate is clamped passing through slotted portions of the slide and anchored in the machine frame, spring means tending to move the slide and shuttle out of operative posi-

tion, a latch adapted normally to maintain the slide and shuttle in operative position against the pressure of said spring means, mechanism for driving the shuttle in timed relation to the needle, a slip joint between the shuttle and the driving mechanism, and means rendered operative upon slipping of the joint to disengage the latch and permit the slide and shuttle to be moved out of operative position.

7. In a sewing machine, the combination with a needle, of a shuttle, a support for the shuttle comprising a slide, spring means tending to move the slide and shuttle out of operative position, a latch member adapted normally to hold the slide and shuttle in operative position against the pressure of the spring, mechanism for driving the shuttle in timed relation to the needle comprising a shaft for driving the shuttle, a gear member loosely mounted on the shaft and actuated in timed relation to the needle, a sleeve keyed to slide on the shaft and adapted to co-operate with the said gear member to provide a slip joint, spring means for holding the sleeve in contact with the said gear member, and a flange formed on the sleeve adapted upon slipping of the joint and consequent axial movement of the sleeve to trip the latch member and permit the movement of the shuttle out of operative position.

In testimony whereof I have signed my name to this specification.

BERNARD T. LEVEQUE.
